KEY CUTTING MACHINE

Frederick E. Fowler, Detroit, Mich., assignor to
 F. W. Stewart Manufacturing Company, a corporation of Illinois

Application February 11, 1933. Serial No. 656,281

16 Claims. (Cl. 90—13.2)

My invention relates to improvements in key cutting machines adapted to cut keys of the desired contour, identified by code numbers, as well as to duplicate existing keys.

Such machines as have been available heretofore of the code type, are elaborate and costly and require certain care in making the initial adjustments necessary.

The general object of this invention is to provide a machine which is comparatively simple and inexpensive, but which has an exceedingly wide range of use, particularly in the field of automobile ignition keys and door keys, being adapted to produce, without elaborate adjustment or skillful handling, practically any standard make of key for any automobile in commercial use.

A more specific object is to provide a machine wherein the spacing of the notches in the finished key is determined by a special notched bar or spacer clamped to the usual movable carriage forming a part of such machines, whereas the depth of said notches is determined by an adjustable depth plate mounted on the relatively fixed frame of the machine.

Another object is to provide a machine of this character, wherein a plunger is located between the spacer on the carriage and the stationary but adjustable depth plate on the frame, where by said carriage, when moved toward the cutting tool will have its movement limited by engagement of the spacer with said plunger, the latter having a variable yielding movement, depending on the adjustment of the depth plate behind it, thus providing for the cutting of notches of predetermined and different depths.

A further object is to provide one form of such a machine with a plurality of notched depth bars each of which determines the notch depths of all of the keys of this character manufactured by one company.

An additional object is to provide another form of such a machine with a single dial or disc which may be adjusted to determine the notch depths of all of the keys of all of the manufacturers, on the market, whereby any such key may be made by changing only the spacer, of which there is a different one for each manufacturer.

Other objects and advantages will be apparent from a consideration of the more detailed description which follows.

In the accompanying drawings I have illustrated two commercial embodiments of the invention.

Fig. 1 is a top plan view of one form of mechanism;

Fig. 2 is an end elevation thereof;

Fig. 3 is a section on the line 3—3 of Fig. 1;

Fig. 4 is a section on the line 4—4 of Fig. 1;

Fig. 5 is a plan view of a typical depth slide plate of different configuration from the one mounted in the machine in Fig. 1;

Fig. 6 is a typical spacer key of a different configuration from the one shown mounted in said machine;

Fig. 7 is a top plan view of another form of mechanism; and

Fig. 8 is an end elevation thereof with certain parts broken away.

The machine comprises a suitable base 10, preferably in the form of a casting having integral upright standards or posts 11 and 12 at the right hand end and near the left hand end thereof respectively, as viewed in Fig. 1. The right hand post 11 has a rotatable shaft 13 journaled in its upper end with a grooved pulley or fly wheel 14 secured thereto whereby said pulley may be rotated by a cord in the groove thereof and driven by an electric motor or other mechanical means, or said wheel may be rotated by hand by means of the handle 15, thereby rotating the cutting or milling wheel 16 which is secured to said shaft by the nut 17.

Near the base of the machine is a fixed shaft 18 supported by a pair of lugs 19 which are preferably integral with said base and located near what may be considered the front thereof. A movable frame or carriage 20, in the form of a casting, is supported at its lower end on said shaft 18 and may be slid back and forth on said shaft and also swung about the same as a pivot, as indicated by the dotted line and full line positions in Fig. 2. When the machine is not in operation, the arm 20 is swung downwardly until the handle 21 by which it is manipulated, rests on the bench or table. When it is in use it is swung to the full line position, toward the cutting tool, and in any intermediate position it may be slid back and forth on the supporting rod 18 for a purpose hereinafter explained.

The key blank 22, in which notches are to be ground by the cutting wheel or cutting tool, is clamped in place on the right hand side of said carriage 20, as shown in Fig. 1. Said blank has the usual shoulder 23, on the side in which the notches are to be cut and rests, in the position in which the parts are shown in Fig. 1, on a ledge or horizontal surface 24 slightly below the top of the carriage or casting, the latter having also an

intermediate, vertical shoulder 25 against which said blank is positioned. Said blank is held in a place between said horizontal surface 24 and a loose plate 26, by a wing nut 27 screwed down over a threaded shaft or bolt 28, thus forming a small vise. The usual small stop 29 is pivoted at 30 to the carriage and serves to limit the insertion of the key blank in the vise, being engaged by the shoulder 23. After said blank is clamped in place, the stop is swung down.

In cutting the notches, the operator grasps the handle and swings the carriage from inclined position to substantially vertical position, pressing the key blank against the rotating cutting or milling wheel to cut one notch, then shifting the carriage laterally, cutting another notch, and so on. The depth of the various cuts is limited by a stop engaged by the carriage in its rearward swing, as hereinafter described and the lateral spacing of said notches is determined by a spacer 31 which may, for convenience, have the general shape of a key having notches therein at definite intervals. A number of such keys, or spacers, are available, each lock manufacturer having a different spacing. Thus each machine is equipped with a spacer representing each different manufacturer. The appropriate spacer is inserted in a second vise at the left hand side of the frame or carriage 20, the individual clamp parts being numbered 24' to 30' inclusive, to indicate parts corresponding to those described in connection with the other vise.

The depth of the various notches cut is determined, in this particular machine, by a depth slide plate 32, of which a considerable number are available, representing the depth of the key notches employed by the different lock makers. One of these slide plates is required for each make of key, but the notches in one plate provide all the various depths used by that one manufacturer. For example, the depth plate shown in Fig. 1, marked "Basco" has notches which increase in depth from right to left and are numbered 1, 2, 3, 4, 5, representing all the depths of the notches found in Briggs and Stratton Company's automobile keys. The sixth notch, which is the deepest, is intended in this instance as a convenience in duplicating existing keys. The Basco spacer shown also in Fig. 1 has five notches. Other spacers may have a greater or less number of notches and at greater or less distances apart.

The appropriate depth plate, in conjunction with the plunger 33, furnishes the fixed stop against which the frame 20 is swung repeatedly in grinding the several notches required. Said plunger 33 has a wedge shaped stop in the form of a small block 34, adjustably secured to it, which stop, during the grinding operation, is pushed back against the bottom of one of the recesses in the slide plate 32, against the action of the helical spring 35, when engaged by one of the notches in the spacer 31, as shown in Fig. 1, whereupon the vertical front edge of said plunger constitutes the fixed stop.

It will be understood that the notch in said spacer engages said plunger before the grinding wheel begins to cut the notch in the key blank 22 and as the pivoted frame 20 is pressed rearwardly, the engagement of said plunger in said notch prevents lateral movement of said frame on the supporting bar 18.

To grind another notch the frame is swung away from the grinding wheel, moved laterally to the desired position and again pressed toward

the same after moving the depth plate 32 to bring the appropriate notch in register with the stop 34. In this way teeth may be ground corresponding to any of the notches in said depth plate whereas the lateral spacing of said teeth is determined by the notches in the space plate or key 31.

80

The mounting for the plunger 33 and the depth plate 32 will now be described more in detail. On top of the post or pedestal 12 is mounted a head 36 or small casting adapted to be slid back and forth from right to left, as viewed in Fig. 1 and clamped in adjusted position. It is guided in this movement by a rib 37 on top of said post, received within a notch 38 in the bottom of said head and forming ways. Said head is held in the desired position by a screw 39 and is adjusted so that the distance between the left hand side of each vise is the same as the distance between the vertical front edge of the plunger 33 and the center or edge of the cutting wheel 16. This adjustment is determined by loosening the screw 39, and placing two identical keys in the two vises against the stops 29, 29', the notches in each key necessarily being the same distance from the shoulder on said key. The pivoted frame 20 is then swung toward the cutter (which is not rotated at this time) after said frame is moved back and forth until said cutter can enter one of the notches in said key, whereupon the block or head 36 may be adjusted until the plunger 33 enters the corresponding notch in the key in the left hand vise, after which the screw 39 may be tightened to clamp the head in place. This adjustment need not be changed for long intervals of time.

115

120

125

130

135

The head 36 also has a notch 40 in the upper surface thereof to receive the depth plate or bar 32, the latter being confined by a bar 41 screwed to said head, said depth plate being 115 slidable freely back and forth in the groove provided, to bring any of the notches therein in registration with the stop 34 on the rear of the plunger 33. In order to properly adjust the machine for the depth of cut, the stop 34, 120 of which is bifurcated at its forward end, may be adjusted forward or backward on the plunger and then secured by means of a screw 42 and a washer 43 beneath the head of the screw, bearing on said bifurcated portion. Said plunger has 125 a flat portion 44 on top of the same on which said adjustable stop rests. This depth adjustment is made also by placing blank keys in each vise, pressing the pivoted frame back to the desired position, and tightening the screw 42', the 130 adjustment preferably being such that with the plunger pressed back against the appropriate duplicating notch in the slide plate, as for example the left hand notch in slide plate 32, the cutter, if rotated, will make only a light scratch 135 across the key.

Where the machine is to be used merely to duplicate an available key, the latter is clamped in the left hand vise and the key blank in the right hand vise. The plunger 33 need not yield 140 but may be clamped in the proper position (determined by using the duplicating notch just referred to) by means of a set screw having a knurled head 45, whereupon by pressing the swinging frame toward the grinding wheel and 145 intermittently giving said frame a step by step movement from right to left, a duplicate key will be formed, as will be readily understood.

The machine described is used primarily in connection with a code. Assuming, for exam- 150

ple, that an ignition key has been lost, it is necessary first to remove the ignition lock and examine the number thereon, which is normally concealed. These locks, as used commercially, are manufactured by a limited number of companies, each of which makes about two hundred fifty different keys. Assume, for example, a Briggs and Stratton lock, there will be provided a single depth plate 32 and a single spacer 31, each marked Basco. After noting the number on the lock, a code book, especially designed for this purpose, is consulted which gives a number, for example one having five digits. Assume, for example, a lock, No. A-810 Basco. The index shows a corresponding combination number, 35153. Another part of the code shows the number of the blank key to be used, i. e. 173. The blank is inserted in the right hand vise with its shoulder against the stop. The spacer marked Basco is then inserted in the left hand vise against the corresponding stop and both stops then swung downwardly out of the way. The Basco depth slide is then inserted in its slot with notch 3 in line with the plunger. The cutter is turned and the key is forced toward the same as far as it will go. This first cut is to be made next to the shoulder of the key. Since the combination number, 35153, begins and ends with the digit 3, the carriage is moved over to the last notch and another cut made therein of the same depth as the first cut. The depth slide is then moved to bring digit 5 in line with the plunger and the second and fourth cuts made without changing the adjustment since the same digit appears twice in the second and fourth positions. The depth slide is then adjusted, with the plunger opposite the digit 1, and the operation repeated. In this last instance there is no number 1 notch, but the edge of the slide constitutes the abutment.

As illustrating a depth plate having notches different from the ones shown in Fig. 1, see Fig. 5 in which a Yale depth plate 46 is shown. Fig. 6 shows the corresponding spacer key 47. All of the various spacer keys have a shoulder corresponding to the shoulder 48 shown in this figure, which limits the depth of insertion of said spacer in the left hand vise just as the corresponding key blank has a corresponding shoulder to limit the position of the same with reference to the right hand vise.

It will be noted that the adjustable head 36 is more or less in alignment with the axis of rotation of the grinding wheel, it being approximately the same height and, in general, being mounted toward the rear of the supporting base plate. The inward or rearward movement of the horizontal plunger is limited by the notched edge of the adjustable depth plate, which in this instance is a rectangular plate adjustable lengthwise, i. e. transversely with reference to the axis of the plunger, although it is obvious that various other forms of plate may be adjustably mounted to the rear of said plunger to limit the inward movement thereof to various predetermined positions. The adjustable depth plate and the plunger are mounted on a stationary part of the machine and the carriage is swung toward the same as well as toward the grinding wheel, the plunger being positioned between the spacer and the depth plate.

In Figs. 7 and 8 are shown a modification in which the adjustable depth plate instead of being adjustable back and forth in a direction parallel to the axis of rotation of the grinding

wheel, is in the form of a disc rotatable about a vertical axis, eccentric with respect to said disc, so that upon rotation of the latter the effective radius of the disc will be varied, without notching the periphery, although notches may be provided as a further alternative either with an eccentric mounting or concentric mounting of the disc.

The other portions of the machine may be assumed to be the same as those previously described and corresponding reference numerals have been applied thereto. The disc 50 is rotatable about a vertical pin 51 in the form of a threaded shaft having a wing nut 52 thereon to clamp the disc to the head 36. The numbers applied to the graduations around most of the circumference might be arranged as a continuous series, although to avoid bringing said numbers too close together and to render said graduations more readily distinguishable, said graduations are arranged in two groups on opposite sides of the disc, as shown, numbers 1 to 45 being grouped on one side and numbers 46 to 90 being grouped on the other side. Between the two is a line marked Dup, i. e. duplication, indicating the effective radius to be used in limiting the rearward movement of the plunger when an available key is to be duplicated. The periphery of the disc provides sufficient available space to enable one disc to be used as the depth plate for practically all of the keys now on the market, of the tumbler type, as the eccentric throw is sufficient to correspond to the maximum and minimum depth cuts and all intermediate requirements.

If a new make should be introduced involving deeper notches than ordinarily provided for by the disc plate shown, a duplicate of said disc could be provided having the eccentric opening in a different position to decrease the effective radius in certain positions, or a new disc could be provided to meet the special case, or the stop member 34 could be adjusted on the plunger 33 to permit the latter to recede a greater amount than with the adjustment shown. This latter arrangement is preferable as it provides for an almost unlimited capacity, in cutting keys by code.

While the form of machine just described has the advantage that only one depth plate is required, whereas with the first form of machine described it is necessary to provide half a dozen or more depth bars only one of which can be used at a time, said depth bars have notches therein which do not require as accurate adjustment as the graduated disc, as the notches when engaged by the V shaped end of the stop member make said depth bars self-aligning by the wedging action which takes place.

While the plunger in both cases is provided with a spring by means of which it normally projects out enough to be engaged by the spacer before the key blank engages the periphery of the cutter, it is evident that this preliminary engagement may be insured in other ways and without necessarily using a spring. Various other changes may be made in the form and location of the elements described without departing from the spirit of the invention.

Reference in the specification and claims to the location of the position of various parts as horizontal, vertical and the like, is not intended to limit the same but rather as a convenience in defining the relative position of such parts and to simplify the description.

I claim:

1. In a key cutting machine, a base, a movable

- frame supported thereby and having a pair of vises thereon for holding a spacer and a key blank, a cutting tool mounted on said base toward which said frame is moved to cut said blank, 5 a stop mounted on said base and with respect to which said frame is moved back and forth to determine the location only of the cuts lengthwise of said key blank and positioned to be engaged by said spacer during movement of said frame 10 toward said cutting tool to limit the depth of the cut, at the desired point on said key blank, and means for adjusting the position of said stop to provide for cuts of different depths in the same key blank.
- 15 2. In a key cutting machine, a base, a cutting tool thereon, a frame on said base movable toward and away from said cutting tool and movable at right angles to said first movement, vises on said frame, one adapted to hold a key blank and 20 the other holding a spacer member having notches therein of uniform depth and spaced apart distances corresponding to the spacing of the notches to be cut in said key blank, a depth plate adjustably mounted on said base, a stop between 25 said depth plate and spacer member to be engaged by one of the notches in the latter when said frame is moved to cut said key blank, said stop engaging said depth plate also whereby the latter, in various positions of adjustment, determines the limiting positions of said stop and 30 hence determines the depth of the cuts in said key blank.
- 35 3. In a key cutting machine, a movable frame having a pair of vises thereon for holding a spacer and a key blank, a cutting tool toward which said frame is moved to cut said blank, a yielding stop to the rear of said spacer, located to be engaged thereby and to limit the depth of the cut and an adjustable plate behind said stop to position the same.
- 40 4. In a key cutting machine, a movable frame having a pair of vises thereon for holding a spacer and a key blank, a cutting tool toward which said frame is moved to cut said blank, a yielding 45 mounted plunger engaged by said spacer and an adjustable depth controlling member to limit the yielding movement of said plunger and thus insure cuts in said key blank of various predetermined amounts.
- 50 5. A key cutting machine comprising a base, a rotatable cutting wheel thereon, a frame pivotally and slidably supported on said base whereby its upper end may be swung toward and away from said wheel and moved in a direction parallel to the axis of rotation thereof, a pair of 55 vises on said frame for holding a spacer and a key blank, a head also supported by said base, a plunger mounted in said head, a spring normally projecting said plunger toward said spacer and a plate adjustably supported by said head, behind said plunger, to permit a variable inward movement of said plunger when engaged by said spacer.
- 60 6. A key cutting machine comprising a base having a pair of standards thereon, a cutting wheel supported by one of said standards, a head supported by the other of said standards in approximate alignment with the axis of rotation of said wheel, a frame pivotally and slidably supported on said base, a pair of vises on said frame, a plunger supported by said head, a spring permitting said plunger to yield inwardly and a notched depth plate adjustably supported by 70 said head to the rear of said plunger to limit the inward movement thereof.
- 75 7. A key cutting machine comprising a base having a pair of standards thereon, a cutting wheel supported by one of said standards, a head adjustably supported on said other standard to vary its distance from said wheel, a plunger received in an opening in said head, a stop member adjustably secured to said plunger and a depth plate slidably mounted on said head at right angles to the axis of said plunger to limit the inward movement of the same. 80
- 85 8. In a key cutting machine, a supporting member, a horizontal plunger supported thereby, a bifurcated stop member on said plunger, a screw for adjustably securing the same in position, a notched depth bar transversely adjustable with reference to the axis of said plunger and mounted to have one of its notches engaged by said stop member and a spring normally holding said plunger and stop member out of engagement with said notches. 90
- 95 9. In a key cutting machine, a base with a pair of vertical standards thereon, a cutting wheel rotatably supported by one standard, guideways on said second standard, a head adjustably mounted on said guideways to vary its distance from said wheel, a plunger received within an opening in said head and having a vertical edge on its protruding end, a spring behind said plunger normally causing it to protrude, a stop member adjustably mounted on said plunger and accessible through a slot in said head, a notched depth plate received in a transverse slot to the rear of said plunger to be engaged by the stop thereon when said plunger is pushed inwardly and means overlying said depth plate to confine it in said slot. 100
- 100 10. In a key cutting machine, a base with a pair of vertical standards thereon, a cutting wheel rotatably supported by one standard, guideways on said second standard, a head adjustably mounted on said guideways to vary its distance from said wheel, a plunger received within an opening in said head and having a vertical edge on its protruding end and a set screw for holding said plunger in adjusted position. 105
- 110 11. In a key cutting machine, a base, a rotatable shaft supported thereon, a cutting wheel on said shaft, a head spaced from said wheel in substantial alignment with said shaft, a carriage 115 slidable in a direction parallel to said shaft and pivoted to swing toward said wheel and head, spaced vises on said carriage, a spacer clamped in one of said vises, the other being aligned with said wheel, a depth plate movably mounted on said head, a plunger mounted on said head between said plate and said spacer to be engaged by the latter and moved until obstructed by the former and means for shifting said carriage when said engaging parts are disengaged. 120
- 125 12. In a key cutting machine, a base, a rotatable shaft supported thereon, a cutting wheel on said shaft, a head spaced from said wheel in substantial alignment with said shaft, a carriage 130 slidable in a direction parallel to said shaft and pivoted to swing toward said wheel and head, spaced vises on said carriage, a spacer clamped in one of said vises, the other being aligned with said wheel, a disc rotatably mounted on said head, a plunger mounted on said head between said disc and said spacer to be engaged and moved by the latter into contact with said disc and means for holding said disc in various positions of adjustment with reference to its axis of rotation. 135
- 140 13. In a key cutting machine, a movable frame having a pair of vises thereon for holding a spacer 145

and a key blank, a cutting tool and an eccentrically mounted plate toward which said frame is moved in cutting said blank, said plate being rotatable to provide a variable stop to limit the movement of said frame and thus vary the depth of the cuts.

14. A machine as in claim 13 in which the periphery of each half of the plate is eccentric with reference to the axis of rotation thereof, the eccentricity of one half being greater than the other half.

15. In a key cutting machine, a base, a movable frame thereon having a pair of vises for holding a spacer and a key blank, a cutting tool toward which said frame is moved to cut said blank, a longitudinally movable pin supported by said

base to be engaged by said spacer, and an eccentrically mounted plate to the rear of said pin to limit the movement of the same and of said frame when the latter engages the former.

16. In a key cutting machine, a base, a movable frame thereon having a pair of vises for holding a spacer and a key blank, a cutting tool toward which said frame is moved to cut said blank, a longitudinally movable pin supported by said base to be engaged by said spacer, and an eccentrically mounted plate to the rear of said pin to limit the movement of the same and of said frame when the latter engages the former, said pin being formed of a plurality of adjustable parts to vary its effective length.
